UNITED STATES PATENT OFFICE

130,324

DESIGN FOR A SAND URN

Edward George Harvey, Fort Thomas, Ky., assignor to The F. H. Lawson Company, Cincinnati, Ohio, a corporation of Ohio

Application August 28, 1941, Serial No. 103,074

Term of patent 7 years

To all whom it may concern:

Be it known that I, Edward George Harvey, a citizen of the United States and a resident of Fort Thomas, in the county of Campbell and State of Kentucky, have invented a new, original, and ornamental Design for a Sand Urn, of which the following is a specification, reference being had to the accompanying drawing, forming a part thereof.

In the drawing:

I claim:

The ornamental design for a sand urn, substantially as shown.

EDWARD GEORGE HARVEY.
